F. JOSEPH SHEFFERLY, OF DETROIT, MICHIGAN.

Letters Patent No. 73,202, dated January 7, 1868.

IMPROVEMENT IN PRESERVE-JARS.

The Schedule referred to in these Letters Patent and making part of the same.

TO ALL WHOM IT MAY CONCERN:

Be it known that I, F. JOSEPH SHEFFERLY, of Detroit, in the county of Wayne, and State of Michigan, have invented a new and improved Preserve-Jar; and I do hereby declare that the following is a full, clear, and exact description thereof, which will enable those skilled in the art to make and use the same, reference being had to the accompanying drawings, forming part of this specification.

This invention relates to a new and improved method of manufacturing jars for preserving fruits and other articles of diet of a similar nature; and it consists in the novel and improved method of sealing or securing the cover of the jar to the neck, as will be hereinafter described.

Figure 1 represents a vertical section of a preserve-jar, with the top or cover secured according to my invention.

Figure 2 is a top view of the cover, showing the ears or lugs by which it is turned in and out of the neck, in the act of sealing and unsealing.

Figure 3 is a bottom view of the cover, showing two curved inclined planes, the inclines of which are placed in opposite directions.

Similar letters of reference indicate corresponding parts.

A represents the jar, and B the cover. The form of the neck of the jar is seen in fig. 1, at C, and the oblique line $\alpha\alpha$ represents the upper and the lower surfaces of two semicircular inclined planes, which surround the inner surface of the neck.

It will be seen that the neck is shelving, or inclines inward, and the upper portion of the cover is of corresponding form, as seen at b, so that, when packing is inserted between these two surfaces, it would become tightly wedged if the cover should be raised. Now this is exactly my method of sealing the jar.

d represents a ring of rubber or other suitable packing. The inclined planes or wedges on the cover and in the neck (two on each) are placed in relation to each other, and act upon each other like the threads of a screw-bolt and nut. The cover drops down into the neck of the jar, as seen in the drawing, fig. 1, with the inclines on each part in contact with each other, so that, by turning the cover to the right, it is raised, and lowered if turned to the left.

To seal the can, the rubber ring d is placed on the cover, as seen in the drawing, (when the cover is at its lowest position,) and then crowded down to the bottom of the space i, when the cover is secured by turning it, which presses the packings tightly against the neck of the jar, thus sealing it. ff represent lugs or ears on the cover, which allows a stick to be used as a wrench for tightening or loosening it.

By this method of sealing, glass jars and glass covers may be used with the greatest facility, and covers which vary in size may be used on the same jar without inconvenience. To unseal the jar, the cover is turned to the left, which loosens the packing, which is readily removed, when the cover is taken out without difficulty.

Having thus described my invention, I claim as new, and desire to secure by Letters Patent—

Sealing a preserve-jar by raising the cover in the neck of the jar, instead of lowering it, substantially as described.

F. JOS. SHEFFERLY.
